(Cl. D52—1)

To all whom it may concern:

Be it known that we, James D. Burke and Fuller A. Crooks, citizens of the United States of America, residing at Los Angeles, in the county of Los Angeles, State of California, have invented a new, original, and ornamental Design for a Torque Meter, of which the following is a specification, reference being had to the accompanying drawing forming a part thereof.

Fig. 1 is a front elevational view partially in

section of a torque meter showing our new design,

Fig. 2 is a top plan view thereof, and

Fig. 3 is an elevational view of the same in cross-section taken on the plane 3—3 of Fig. 1.

We claim:

The ornamental design for a torque meter, as shown.

JAMES D. BURKE.
